UNITED STATES PATENT OFFICE.

JOSEPH MITCHELL, OF CHADD'S FORD, PENNSYLVANIA, ASSIGNOR OF ONE-HALF TO LOUIS H. HOOPES, OF SAME PLACE.

TRICYCLE.

SPECIFICATION forming part of Letters Patent No. 443,292, dated December 23, 1890.

Application filed September 9, 1890. Serial No. 364,448. (No model.)

To all whom it may concern:

Be it known that I, JOSEPH MITCHELL, a citizen of the United States, residing at Chadd's Ford, in the county of Delaware, State 5 of Pennsylvania, have invented a new and useful Improvement in Tricycles, which improvement is fully set forth in the following specification and accompanying drawings.

My invention relates to improvements in tricycles; and it consists, first, of a tricycle or other velocipede having a swinging seat the oscillation of which operates mechanism connected therewith for rotating the running wheels; second, of mechanism, substantially 15 as described, for rotating the running wheels; third, of means, substantially as described, connected with the operating mechanism of the running wheels for alternately disengaging and engaging the racks of the reciprocating rods thereof with the axle of the said running wheels, and, fourth, of the combination of parts hereinafter set forth.

Figure 1 represents a side view of a part of a tricycle embodying the features of my invention, one of the wheels and a portion of the frame being removed to more clearly show the other parts. Fig. 2 represents a rear view of the tricycle shown in Fig. 1. Fig. 3 represents a plan view of the guiding-arms and a 25 portion of the operating-arms of the device. Fig. 4 represents a vertical sectional view of a part of the device, showing the means for limiting the movement of an operating arm. Fig. 5 represents an enlarged view of one of 30 the outer ends of the rod, which is rigidly connected with the oscillating shaft in the upper part of the frame of the machine. Fig. 6 represents a partly side and partly sectional view of a wheel, showing the spoke-connections with the hub, rim, and tire.

Similar letters of reference indicate corresponding parts in the several figures.

Referring to the drawings, A designates a tricycle having the running wheels B mounted 45 on the axle C and provided with a steering-wheel D.

The frame E of the machine has a base or reach F, to which is pivotally secured at its front end a forked piece G, in which is journaled the axle of the steering-wheel D, and

to the upper end of which is secured the steering-arm H.

J designates an ear on the boss K of the piece G, the same furnishing a bearing for a stationary shaft L, on which are mounted 55 sleeves M, with which are connected the arms N, the latter being provided with the handles P. The movement of the said arms is limited by means of pins Q, secured to the shaft L, and freely projecting into slots R of 60 the sleeves.

On the axle C and near the wheel B are loosely mounted the standards S of the frame, the said standards, which are forwardly inclined, having in their upper ends bearings 65 for a rock-shaft T. Secured to the boss K is the front or lower end of the backbone or reach V of the frame, the rear forked end thereof being loosely mounted on the shaft T near the upper ends of the standards S. 70 Fastened to the shaft T are the arms W, and to the opposite sides and ends of a cross-arm X, which is rigidly secured to the central portion of the shaft T, are the depending arms Y. The said arms W and Y are near their 75 lower ends provided with supports for the removable seats Z, each of which has one of its ends resting or supported on an arm W and the other end on an arm Y, so that the torsional strain upon the shaft T, caused by 80 the swinging of the seat and its connected arms, is not limited to one part of the shaft, but is distributed over the same. One set of the arms W and Y are in advance of the other at the seat portion thereof a distance corresponding to the distance of the inner end of 85 one of the arms N in front of the inner end of the other arm N, so that the occupant of each seat is at an equal distance from the handle of the arm which he bears or pushes 90 against. A foot-rest A' is secured to the lower end of each of the frames which carries a seat.

On the axle C is rigidly mounted a gear-wheel B', and to the ends of the cross-arm X of the shaft T are secured alternately-reciprocating rods C' D', which have racks or toothed portions E' F' meshing with said gear-wheel B', so as to rotate the same, and thereby the running wheels B of the device. To 100

insure the proper engagement and disengagement of the said racks, respectively, so that the axle C will be rotated in the same direction by the continuous oscillation of the shaft 5 T and arm X, the following described mechanism is employed. In connection with the rods C' D', which are inclined, the additional inclined rods G' and II', respectively, are used. The upper end of each rod of the 10 pairs of rods C' G' and D' II' is divided and has a free bearing on one of two detachable oscillating blocks J', which blocks are secured in recessed portions of the ends of the cross-arm X, by means of screws K', which 15 operate in the ears K² of the cross-arm.

On the back of each of the rods C' D' are the projections L', and on the adjacent faces of the rods G' II' are the projections M', which latter are adapted to rest on or against the 20 said projections L' at each alternate movement of each of the rods, so that the racks are kept in engagement or mesh with the gear-wheel B' at such movement. Attached to the frame E of the machine are the arms 25 N', which are provided with cushions or buffers P', against which the lower ends of the rods G' and II' strike at the end of their downward movement. A roller Q', mounted on the frame, serves to keep the rack-rod of 30 each pair of rods in contact with the gear-wheel B' when the projections M' are on the projections L', and a toothed cam or eccentric R', pivoted to the frame and meshing with a toothed portion of the rod C', serves 35 to disengage the rack E' of said rod C' from engagement with the gear-wheel B' when the said rod is descending.

A guard S', secured to the frame of the machine, serves to shield the gear-wheel B' from 40 contact with the clothes of the occupants of the seats Z.

To the base F of the frame are attached 45 hangers carrying the pins T' to assist the riders in getting on or off the machine. A 50 brake U', consisting of a pivoted arm V', carrying a rubber roller for contact with the gear-wheel B', is kept normally from operation by a spring W'. To operate the steering-arm II, the chains X' are secured to its ends and to 55 pivoted levers Y' on one of the arms N.

The operation of the device is as follows: 55 A party or parties on either or both of the seats Z, by bearing against a handle on one of the arms N, will cause the seats to be swung backward, so that the frames thereof will rock the shaft T, thus oscillating the cross-arm X, lowering the front end thereof and raising the rear end. By raising the said rear end the rods D' II' are lifted so that the 60 rack F' of the rod D', which is in engagement with the gear-wheel B', owing to the projections M' being on the projections L', will rotate the said wheel, thereby advancing the tricycle. At the same time the rack E' of the 65 descending rod C' is out of engagement with the gear-wheel B', owing to the action of the

toothed cam or eccentric R', which, working with the rod C', has lifted the same from off the gear-wheel B', the inclined faces of the projections L' M' and the oscillating 70 bearing block J' readily permitting the movement of the rods C' and G' on the other, so that the projections M' are no longer on the projections L', thereby allowing the closer approach to each other of the said rods. 75 When the seat reaches the end of its backward movement and the rod G' is at the end of its downward stroke, the lower end thereof abuts against a cushion P', so that the projections M' will ride on the projections L', 80 and thus bring the rack E' of the rod C' into engagement with the gear-wheel B', so that on the upward movement of the said rods C' G' the wheel B' will be rotated in the same direction as it was when engaged by the rack 85 F' of the rod D', thereby farther advancing the tricycle. When the rack F' in its ascent has risen so as to be out of engagement with the gear-wheel B', the rod G' is no longer held by the said wheel and the roller Q' in close 90 contact with the rod D', and being formed of greater weight than the rod D' and bearing on the opposite side of the center of the block J' from the said rod D' it will oscillate the block J' so as to descend, thus raising the 95 rod D' so that the projections M' no longer bear against the projections L', but pass below the same, thus permitting the rack F' of the rod D' to fall away from engagement with the gear-wheel B', so that on the descent of 100 the rods D' II' on the forward movement of the seats the said rack F' will not be in contact with the said gear-wheel. As the rod II' reaches the end of its downward stroke it is stopped by a cushion P', and the projections 105 M' and L' of the said rods are again brought into engagement, so that the rack F' and gear-wheel B' are meshed for the upward movement of the rod D'. It will be seen that the racks of the rods C' and D' are alternately 110 meshed with the gear-wheel B', thus continuously rotating the same.

In Fig. 6 the spokes are shown as secured to the rim and hub of a wheel by inserting one end of a spoke Z' into a countersunk 115 opening A² in the tire B² and then into a hollow hub C² and securing it by nuts D² E², the other end of the spoke, which is provided with a head F², resting in the countersunk opening of the tire. 120

Having thus described my invention, what I claim as new, and desire to secure by Letters Patent, is—

1. In a velocipede, the combination of an axle having a gear-wheel secured thereon, a 125 frame with a rock-shaft having a cross-arm, rods pivoted to said arm and provided with racks meshing with said gear-wheel, and a swinging seat, substantially as described, for oscillating said rock-shaft, substantially as 130 and for the purpose set forth.

2. In a velocipede, the combination of a ro-

5 tary axle having a gear-wheel secured thereon, alternately rising and falling rods with racks engaging said gear-wheel, and a swinging seat and connections, substantially as described, for operating said rods, substantially as and for the purpose set forth.

3. The combination of a swinging seat, a rotary axle having a gear-wheel secured thereon, alternately rising and falling rods provided with racks, and mechanism, substantially as described, for disengaging each of said racks from the gear-wheel on each alternate movement and engaging it with the said gear-wheel on its return movement, substantially as and for the purpose set forth.

15 4. The combination of a rock-shaft having a cross-arm extending therefrom, an arm depending from said shaft, an arm depending from said cross-arm, and a seat supported by said depending arms, substantially as and for the purpose set forth.

25 5. The combination of a frame, a rock-shaft journaled therein, a swinging seat for operating said shaft, a cross-arm secured to said shaft, a rotary axle with a gear-wheel secured thereon, rods connected with said cross-arm and having racks adapted to mesh with said gear-wheel during a portion of their movement, substantially as and for the purpose set forth.

30 6. The combination of a frame, a rock-shaft mounted therein, a swinging seat for operating said shaft, a cross-arm secured to said shaft, a rotary axle with a gear-wheel secured thereon, and rods connected with the ends of said cross-rods and each having a rack adapted alternately to mesh with said gear-wheel, substantially as and for the purpose set forth.

40 7. The combination of a frame, a pivoted arm, a shaft, a seat connected with said shaft and adapted to rock or oscillate the same, arms pivotally connected with a cross-arm of the shaft and provided with racks, and a rotary axle with a gear-wheel thereon, substantially as and for the purpose set forth.

45 8. The combination of a rotary axle having a gear-wheel secured thereon, a reciprocating rod having on its face a rack engaging said wheel, and on its back projections a second rod adapted to move with and on said first rod and provided with projections adapted to contact with the projections on the first rod, substantially as and for the purpose set forth.

50 9. The combination of a rotary axle having a gear-wheel secured thereon, a frame with a rock-shaft journaled therein, a cross-arm connected with said rock-shaft, mechanism, substantially as described, connected with said rock-shaft for oscillating the same, oscillating blocks in said cross-arm, rods having divided upper ends bearing on said blocks and provided with racks, a rotary axle having a gear-wheel secured thereon, and mechanism, substantially as described, including said oscillating blocks, for disengaging said racks

from said gear-wheel, substantially as described.

10. The combination of a frame, a rock-shaft with cross-arm, a rotary axle with a gear-wheel secured thereon, a rod with divided upper end and provided with a rack on its face adapted to engage with said gear-wheel, and projections on its back, an oscillating block in the cross-arm, a second rod with a divided upper end and having projections adapted to contact with the projections of the other rod, and a roller between which and the gear-wheel the two rods are adapted to reciprocate, substantially as described.

15 11. The combination of a frame, a rock-shaft with cross-arm, an oscillating block in said cross-arm, a rotary axle with a gear-wheel secured thereon, two sets of reciprocating rods pivotally bearing on said blocks at their upper ends, one of each set having a rack on its face adapted to mesh with the said gear-wheel, and on its back provided with projections each having an inclined side, and the other rod of the set which extends below the rock-rod having projections adapted to contact with the projection of the said rock-rod, a roller, and a cushion or buffer, substantially as and for the purpose set forth.

20 12. In a velocipede, the combination of a frame, an arm having a tubular end with a slot therein, a stationary shaft on which said tubular end is mounted, and a pin secured to the shaft and in the slot, substantially as and for the purpose set forth.

25 13. In a velocipede, the combination of a frame, a rotary axle with a gear-wheel secured thereon, and a spring-controlled arm pivoted to the frame and having a roller connected therewith and adapted to engage said gear-wheel, substantially as described.

30 14. In a velocipede, a frame formed of a base portion with rotary axle journaled therein, two inclined standards having a rock-shaft journaled in their upper ends, and a backbone or reach connected with the front of the base portion and having a forked upper portion loosely connected with the rock-shaft, said parts being combined substantially as described.

35 15. The combination of a frame, two swinging seats connected with a rock-shaft journaled in said frame, and two pivoted handles, one of said seats and handles being on the side and in advance of the other seat and handle, substantially as described.

40 16. In a velocipede, a frame, a steering-wheel, a bearing-piece for the shaft thereof, steering-arms secured to said piece, an arm secured to the frame and provided with pivoted levers, and means, substantially as described, connecting said levers and the steering-arms, said parts being combined as set forth.

45 17. A velocipede having a rotary axle with a gear-wheel secured thereon, an oscillating

cross-arm, an oscillating block in said cross-arm, a rod having a rack on its face and projections on its back, a second rod with projections adapted to contact with the projections on the first-mentioned rod, and a roller against which said second rod bears, the projections of both rods having inclined contact

sides and the said rods being supported on the said oscillating block, said parts being combined substantially as described.
